LIGHTING FIXTURE

Bradford W. Powers, Jr., 5470 Castle Hills Drive,
San Diego, Calif. 92109

Filed Apr. 1, 1966, Ser. No. 1,739

Term of patent 14 years

(Cl. D48—23)

Fig. 1Fig. 2

FIG. 1 is a perspective view of the lighting fixture, depicting hexagon top and bottom plates that are connected by elongated slats which surround an opaque cylinder; and FIG. 2 is a bottom view of the lighting fixture shown in FIG. 1, depicting an opening in the bottom plate.

I claim:

The ornamental design for a lighting fixture, as shown and described.
